Primary Examiner — Wan Laymon*Assistant Examiner* — Clint A Samuel(74) *Attorney, Agent, or Firm* — Mintz Levin Cohn Ferris Glovsky and Popeo, P.C.; Peter F. Corless; Carolina E. Säve(57) **CLAIM**

The ornamental design for a tube with attached cap, as shown and described.

DESCRIPTION

FIG. 1 is a perspective view of a tube with attached cap.

FIG. 2 is a front view of the tube with attached cap.

FIG. 3 is a left side view of the tube with attached cap.

FIG. 4 is a right side view of the tube with attached cap.

FIG. 5 is a back view of the tube with attached cap.

FIG. 6 is a top view of the tube with attached cap.

FIG. 7 is a bottom view of the tube with attached cap; and, FIG. 8 is a second perspective view of a tube with attached cap in a closed position.

The broken lines showing in the drawings are for the purpose of illustrating portions of the article and form no part of the claimed design.

1 Claim, 5 Drawing Sheets(56)
